UNITED STATES PATENT OFFICE.

OSCAR A. SMITH, OF CLEVELAND, OHIO.

PRIMING AND TESTING CUP.

1,327,687.

Specification of Letters Patent. Patented Jan. 13, 1920.

Application filed November 8, 1917. Serial No. 200,869.

To all whom it may concern:

Be it known that I, OSCAR A. SMITH, a citizen of the United States, residing at Cleveland, in the county of Cuyahoga and 5 State of Ohio, have invented certain new and useful Improvements in Priming and Testing Cups, of which the following is a specification.

This invention relates to priming and testing cups for gas engines, the object of the invention being to provide an improved cup having all the advantages of the cups described in my United States Patent No. 1,153,457 dated September 14, 1915 and in 10 my contemporaneously pending application filed October 30, 1917, Serial No. 199,252, and having, however, the further and important advantage that it can be used with motors that are located at an angle such as 15 eight-cylinder and twelve-cylinder motors 20 or inserted at the side of the motor wherever this is desired.

The cups shown in the patent and application referred to would necessarily have to 25 be inserted into the motor casing at the top thereof, since if the cup was located at an angle or at the side of the motor, it would not be practicable to insert the fluid into the cup as it would run out before the valve was 30 opened. It is oftentimes desirable, however, to insert these cups at the side of an engine or into motors located at an angle, and in order to permit this to be done successfully, I provide an improved cup having all the 35 advantages set forth in the said patent and application hereinbefore referred to, while having the further advantage of enabling the cup to be used in a V-shaped motor or to be inserted in the side of the engine as 40 may be found desirable in practice.

In the drawings accompanying and forming part of this specification,

Figures 1, 2 and 3 illustrate vertical sectional views of different styles of this improved cup, Fig. 1 illustrating in dotted lines, the cup partly open and illustrating the cup portion made as an integral structure as shown in my prior patent, while Figs. 2 and 3 illustrate the cup as comprising 45 a body made of bar stock and a cup portion of sheet metal and connected with the body in any desired way; Figs. 4, 5 and 6 are top views respectively of the cup shown in 50 Figs. 1, 2 and 3; Fig. 7 is a top view of the 55 body portion of the cup shown, for instance,

in Fig. 2; and Fig. 8 is a vertical sectional view of the cup shown in Fig. 2.

Similar characters of reference indicate corresponding parts in the several figures of the drawings.

In the present improvement, like that shown in my prior patent and application, the valve is maintained closed by pressure thereon. Moreover by reason of the construction the carbon and soot cannot close 65 or clog up the opening or passageway, since any that forms on the valve is fractured when the valve is opened as the valve passage, by reason of the manner in which the valve opens and closes, is entirely cut off 70 from the combustion chamber of the engine and moreover by means of the present construction, the valve is proof against leakage so that it is always possible to easily manipulate the valve without liability of the 75 carbon injuring the valve seat or valve, and thus the valve can always be maintained tightly seated and so prevent any possible loss of power resulting from an imperfect seating of the valve.

In my prior patent, the priming cup was made in two parts; in my prior application it was made in three; in the present improvement it may be made in either two parts as shown in Fig. 1 or in 3 as shown in Figs. 2 and 80 3.

When made in the manner shown in Figs. 2 and 3, the body portion of the cup may be made from a block or bar stock and the cup portion of sheet metal, as brass or steel, and preferably drawn therefrom so that the 85 body portion may be made upon an automatic screw machine and the parts assembled in some suitable way, as by threading one on to the other as shown in Figs. 2 and 3, or by spinning or peening one part on to 90 the other as shown in my prior application, or in any other desired way. This of course permits the cup portion to be drawn out of sheet metal of any size and design desired, so that the cup portion may be made cheaper 100 and of different designs or sizes, as the cost of drawing the cup of sheet metal and assembling it to the body would be considerably less per cup than to make the cup of an integral structure of brass upon an automatic screw machine. The present improved priming and testing cup, while particularly adapted for gas engines, may of course be used for various purposes. When made as an integral structure it comprises 105 110

a body portion 2 and a cup portion 6 made from a single piece of stock exteriorly threaded at one as the lower end 4,—which threads in the present instance are shown as 5 of the tapered variety, although a straight thread could be used,—for insertion into the engine and provided with a wrench-receiving portion 5 and a cup portion 6 located at an angle to the body portion. The body 10 portion is drilled to form an axial passage 7 having interior threads 8 for a part of its length. Formed lengthwise of the body and shown in the present instance as extending therethrough is one or more openings shown 15 herein as grooves or slots 9, preferably two in number, which slots in the present instance open into the axial passageway. Obviously the openings 9 might be simply holes drilled through the body and opening into 20 the axial passageway at the lower end thereof adjacent to the valve seat, but the slot formation shown is the less expensive way of forming the opening. Of course the upper ends of the openings will communicate with 25 the bottom of the chamber 10 of the cup portion 6, so that gasoline will run from the cup through these openings into the engine when the valve is open. The lower end of 30 the body portion is provided with a valve seat 11 shown herein as of tapered form. The cup portion 6 is provided with an opening 12 extending at an angle to the cup chamber, but in line however with the axial passage in the body portion. This permits 35 the use of a straight stem on the valve member proper. This valve member 13 comprises a valve portion or head 14 shown as tapered, coöperating with the seat of the body portion. It will however be under- 40 stood that any form of valve seat or opening could be used so long as the valve is constructed to bear against the outer end of its seat. This valve member is also provided with an enlarged portion 15 having 45 threads adapted to coöperate with the threads on the walls of the axial passage and a stem 16 projecting from the axial passage into and through the opening 12, and it terminates at its upper end in a bend or 50 handle portion 17 whereby on turning the handle the valve will be either seated or unseated from its seat. In this form it will be observed that the valve member projects as it were, from the side of the cup, the stem 55 thereof intersecting the cup chamber.

In Figs. 2 and 3 the body portion or member is made in substantially the same manner as the body portion of the cup shown in Fig. 1, except that above the wrench-receiving portion there is formed a projecting exteriorly threaded portion 19, on which the neck 20 of the cup portion proper may be turned, the said neck portion as shown in Figs. 2 and 3 being provided with 60 interior threads for this purpose, or if 65

preferred the cup portion 6 may be spun or peened on to the body as shown in my contemporaneously pending application, in which instance of course the body would be made in the manner shown there- 70 in. Of course it will be understood that the cup may be attached to the body in other ways, if found desirable. In the form shown in Fig. 2 the cup chamber is likewise located at an angle to the body, but as the 75 cup chamber is made of sheet metal, as for instance brass or steel, it may be so formed or drawn as to have one side thereof curved as at 21, and thus permit the stem to project through the cup in line with the axial passage of the body without the necessity of projecting the stem through the side of the cup, although this could be done, if found desirable, in the same manner that it is done in Fig. 1. In the form shown in Fig. 3 the 80 cup portion proper 6 has the top thereof practically closed, as at 25, while the opening for the insertion of the fluid is at the side as at 26. The particular form shown in Fig. 3 is more particularly adapted for use 85 when it is desired to insert the priming and testing cup into the side of an engine. 90

Obviously the handle may be bent at any desired point and in the present instance it is so bent as to prevent the tapered portion of the valve from dropping away from the body when the parts are assembled or from opening beyond the desired amount. 95

In the use of the device, gasoline is poured into the cup and when the valve is open 100 it runs through the slots 9 into the cylinder of the engine. Thus it will be seen that when the valve is closed the opening into the body member of the cup at the bottom end of the device is entirely closed by the 105 tapered valve member, so that there is no opportunity for the passage of carbon or soot to the cup or to interfere with the effective closing of the valve, or in any way interfere with the operation of the device so 110 that there is no chance for the valve passage in the body to become clogged, and there is, moreover, no opportunity of one part dropping away from the other into the engine, and the priming of the engine 115 by means of this improved cup is a direct priming, that is to say, the liquid runs directly from the cup into the engine. Moreover, by reason of the formation shown the valve will always properly seat itself and 120 thus prevent any leakage and consequent loss of power in the cylinder. In short in the present improvement as well as that shown in my prior patent the threads of the valve member and body so mesh that 125 there is always a proper fit of the valve on its seat at all points around the seat and of course the stem is bent to form the handle at that particular point which will facilitate the opening of the valve the desired 130

amount without moving the valve away from its seat an unnecessary distance.

It will of course be understood that the various details may be more or less changed 5 without departing from the spirit or scope of the present improvement.

In all forms of the present improvement it will be observed that the opening into the cup chamber for the insertion of the 10 gasoline or fluid is at one side of the valve stem, that is, the perpendicular axis of the opening is transverse to or inclined to the valve stem proper, whether the priming and testing cup proper be made as an integral 15 one as shown in Fig. 1 or with a sheet metal cup portion as shown in Figs. 2 and 3.

It will be observed that the upper portion of the cup, especially that shown in Fig. 1, tapers or flares outwardly so that 20 it is of larger diameter at this point than that portion of the cup which communicates with the axial passage 7. Obviously the formation of the cup is such that the spout of an oil can may be readily inserted 25 thereinto and be properly guided into the cup.

From the foregoing, it will be seen that the present improvement comprises a fitting provided with a threaded nipple 4, a 30 polygonal portion 5 and a portion beyond said polygonal portion having a lateral enlargement forming the cup 6, and that the bore 7 extends longitudinally of the fitting and terminates at its lower end in a conical 35 valve seat 11 while the opposite end of the axial passage 7 merges into an oblique bore forming the cup 6 having a flaring mouth portion and that the bore of the cup intersects the axial bore 7 above the conical 40 valve seat so that both may be closed by a single needle valve 13, which is provided with a threaded stem 15 engaging a threaded portion of the bore 7.

I claim as my invention:

45 1. A priming and testing cup comprising a body having a valve seat and a passageway communicating therewith, a cup at the outer end of said passageway, and a valve adapted to engage said seat and having a 50 stem extending axially through the passageway and also through the cup, the mouth of said cup being located entirely at one side of said stem.

2. A priming and testing cup comprising a 55 body member having a valve seat at one end and a passageway communicating therewith, a cup member at the other end of said passageway, and a valve adapted to engage said seat and opening in the direction of the 60 flow of the fluid through said passageway and having a stem provided with threads and extending axially through the passageway and also through the cup member, the mouth of said cup member being located 65 entirely at one side of said stem, one of said

members having threads adapted to cooperate with the threads of the stem.

3. A priming and testing cup comprising a body having a valve seat and a passageway communicating therewith, a cup at the 70 outer end of said passageway, and a valve adapted to engage said seat and having a stem extending axially through the passageway and also through the cup at an inclination to the mouth of said cup. 75

4. A priming and testing cup comprising a body having a valve seat at one end and a passageway communicating therewith, a cup at the other end of said passageway, and a valve adapted to engage said seat and 80 opening in the direction of the flow of the fluid through said passageway and having a stem extending axially through the passageway and also through the cup at an inclination to the mouth of said cup. 85

5. A priming and testing cup comprising a body portion having a valve seat and a passageway communicating therewith, a cup portion having the axis of its chamber extending at an angle to the axis of said 90 passageway, and a valve adapted to fit said seat and having a stem projecting through said chamber and the side wall thereof.

6. A priming and testing cup comprising a body portion having a valve seat and an 95 axial passageway communicating therewith, a cup portion having the axis of its chamber extending at an angle to the axis of said 100 passageway and also having an opening at the side thereof in line with the axial passageway, and a valve adapted to engage said seat and having a stem extending through said axial passageway and said aligned opening.

7. A priming and testing cup comprising 105 a body having a valve seat at one end and a passageway communicating therewith, a cup at the other end of said passageway, and a valve adapted to engage said seat and opening in the direction of the flow of the 110 fluid through said passageway and having a stem extending axially through the passageway and also through the cup at an inclination to the mouth of said cup, said body constructed of a metal block or bar 115 stock and said cup constructed of sheet metal and secured to said body.

8. A priming and testing cup comprising a body having a valve seat and a passageway communicating therewith, a cup at one 120 end of said passageway and having the perpendicular axis thereof extending at an angle to the axis of said passageway, and a valve adapted to engage said seat and having a stem extending axially through the 125 passageway and also through the cup at an inclination to the mouth of said cup.

9. A priming and testing cup comprising a body member having a valve seat at one end and a passageway communicating 130

therewith, a cup member at the other end of said passageway and having its perpendicular axis extending at an angle to the axis of said passageway and terminating at the point of communication of said passageway and chamber, and a valve adapted to engage said seat and opening in the direction of the flow of the fluid through said passageway and having a stem provided with threads and extending axially through the passageway and also through the cup member at an inclination to the mouth thereof, one of said members having threads adapted to coöperate with the threads of the valve stem.

10. A priming and testing cup comprising a body having a valve seat at one end and a passageway communicating therewith and provided adjacent to said seat with internal and external threads, a cup located at the other end of said passageway

and having its perpendicular axis extending at an angle to and substantially meeting the axis of said passageway, a valve adapted to engage said seat and opening in the direction of the flow of the fluid therethrough and having a stem provided with threads adapted to coöperate with the internal threads of the body and extending axially through the passageway and also through the cup at an inclination to the mouth thereof, said stem having a bent handle and said body having a lengthwise extending slot or slots in communication with said passageway and also having a wrench receiving portion, the body being constructed of metal block or bar stock and the cup of sheet metal and secured thereto.

Signed at Cleveland, county of Cuyahoga and State of Ohio, this 5th day of November, 1917.

OSCAR A. SMITH.
